BUFFING WHEEL AND PROCESS OF MAKING
THE SAMEHenry R. Benbow, New Hartford, N. Y., assignor
to Divine Brothers Company, Utica, N. Y., a
corporation of New York

Application February 1, 1943, Serial No. 474,277

12 Claims. (Cl. 51—193)

My present invention relates to buffing wheels. The general purpose of my invention is to provide a long-needed improvement in buffing wheels of the type where the working zone of the buffing wheel has its sections composed of a plurality of rings of flexible fabric puckered at their inner edges and confined by a rigid metal ring and fastened near their inner edges to a central rigid core with the said working zone rings held in distended position during operation of the wheel by centrifugal force, and which type of buffing wheels has said fabric rings made up of long strips of fabric formed in turn from shorter pieces of woven fabric cut on the bias with their angular ends sewed to adjacent short pieces producing seams extending diagonally of said long strips and consequently seams extending diagonally (viz. not radially) inward from the periphery of the said rings. This construction results in the said rings presenting only bias-cut edges at the periphery of the wheel, which give effective service over a long period of use.

This construction of buffing wheel described briefly above has come into very general use but it has long been recognized that it has one very great disadvantage, in fact one which at times makes the buffing wheel dangerous and which at all times is the cause of damage to the work being buffed, and of loss of time.

This difficulty is that after a period of use the forwardly directed acute-angled points in the fabric begin to project outwardly beyond the periphery of the buffing wheel, and as soon as they project appreciably beyond the circle of the periphery of the wheel they make irregular scratches or marks upon the work being buffed which are disfiguring, necessitating rebuffering of the work in order to eliminate them. Obviously time is lost in stopping the machine, trimming off the projecting point or points which are causing the damage, and rebuffering the work. Furthermore if a forwardly projecting point of fabric becomes loosened rapidly enough to give considerable length to the point the point may catch in the article being buffed and push it from the hand of the workman holding the article, or sometimes even loosen the article from the mechanical holder. Obviously if an article being buffed is thus caught by the projecting point of fabric the article may be thrown about the room and cause injury to a nearby workman or damage to materials or machinery in the neighborhood. Of course as soon as a point of cloth thus projects enough so that the workman through his sense of touch realizes that the buffing wheel is

not acting right he stops the buffing wheel and trims off the projecting point. It will be understood that the very rapid rotation of these buffing wheels prevents the projecting point of cloth from being visible.

In practice it takes a little time to stop the buffing wheel and a little more time to find the projecting point or points and to get them cut off in the proper manner. Then the buffing wheel has 10 to be placed in motion again. All these operations consume time and sooner or later the same buffing wheel will have to be stopped again to cut off another point or to trim further down the points cut off as needed before.

15 One purpose of this invention is to improve the said type of buffing wheel or the sections thereof by eliminating such of the acute-angled points of fabric that in practice would project outwardly after reasonable use of the buffing section, and to eliminate these points before the 20 wheel is placed in use. In this way the manufacturer is provided with a buffing wheel of this character that is free of its characteristic defect.

Further purposes of this invention are not 25 only to provide a buffing wheel section from which these undesired forwardly projecting acute-angled points have been eliminated, but to provide a section never having these points and to provide a method of making and assembling 30 buffing wheel sections of this bias-cut edged type of such special construction and shaping of its parts that there will be no forwardly directed acute-angled points of cloth when the section is originally produced, assuming of course that 35 the wheel when used is rotated in its proper predetermined direction.

Further purposes and advantages of my improvement will appear from the specification herein.

40 Fig. 1 is a side elevation or in effect a plan view of one circular side of a buffing wheel section of the old form with a part of the near canvas disk and of several of the annular rings of fabric cut away in order to show the construction 45 of the ring of fabric at the beginning of the further half of the section and also of two layers in the near half of the section.

Fig. 2 is a view similar to Fig. 1 of a buffing wheel section illustrating my improvement.

50 Fig. 3 is a plan view of the piece 15 of fabric including the acute-angled point C cut out from the right-hand side of the fabric ring 10' as shown in the right-hand side of the buffing wheel section of Fig. 2.

55 Fig. 4 is a plan view of the piece of fabric 15

of Fig. 3 after the fabric has been smoothed or straightened out.

Figs. 5, 6 and 7 are plan views on a small scale of pieces of fabric illustrating the steps of producing the long strips of fabric 21 having bias-cut edges.

Fig. 8 is a diagrammatic view showing part of one of the said long strips 21 going to the folding and puckering machine where by my process the acute-angled forwardly projecting points of fabric are eliminated before the fabric is rolled, folded and puckered. And Fig. 9 is a plan view of one of the pieces 15^a so removed.

Fig. 10 is a view similar to Fig. 8, but with the fabric 21 nearest the rolls 30 and 31 of the puckering machine shown as not yet wound upon said rolls while a length of said long strip 21 of fabric still farther to the right is represented not only as not yet puckered but as folded nearly together along its median line.

Referring to the drawings in a more particular description and first to the old form, it will be seen that the buffering wheel section of Fig. 1 is composed of a plurality of annular rings 10 of woven fabric fastened at their inner portion to the central rigid core 11. These rings 10 are in effect built up of long strips 21 of woven fabric which are in turn built up of shorter pieces 12 of fabric cut on the bias with the reversely arranged diagonal ends of the adjacent pieces 12 sewed together by seams 13 which extend transversely of the long strips 21 but in a slanting or diagonal direction across said long strips, and in the rings extend inwardly from the periphery of the rings 10 of a section in a slanting direction (that is, not radially disposed) as at seams 14.

Following a commercial development of the folding and gathering device of Levett's Patent No. 1,296,409 of March 4, 1919, enough of the long strip of fabric 21 is wound upon two aligned but spaced cylinders to make a roll of fabric having layers corresponding in number to one-half the number of rings 10 in the desired buffering wheel section; then the fabric midway the axis of the roll is pushed or drawn in by suitable members moving radially inwardly to the desired extent to press the median ring of the roll of fabric down into the recess between the adjacent ends of the cylinders and closely to the periphery of the cardboard core 11 removably mounted between the adjacent ends of the cylinders. This operation puckers the median ring of the roll of fabric and while that part is held compressed and puckered one cylinder is removed and one-half of the roll is drawn out axially so that the strong rigid ring 15 preferably of metal can be and is placed in position outside the compressed median zone of the roll of fabric closely adjacent the puckering member to hold the fabric compressed and puckered, and then the two halves of the fabric are arranged to extend radially outward from the core 11 and the set of annular rings 10 held to the core 11 by the metal ring are removed as one assembled unit requiring only the stitching on or other strong permanent fastening of the heavy fabric disks 17 to the core and the rings 10 as by the inner and outer annular rows of stitches 18 and 19 to complete the making of the section of the buffering wheel.

Ordinarily a large distinctly marked arrow 16 will be stamped or otherwise printed upon the outer face of one disk of canvas 17 to indicate the direction in which this buffering wheel section should be rotated. As well understood in the art this is dictated by the construction of the

wheel so that the final free end 20 of the strip fabric in the outermost ring 10 will go by the work W in a trailing relation so that the end 20 of the fabric will never get caught in the work.

5 These diagonal seams 14 in the annular rings 10 of fabric are in one sense the price at which the diagonal cut edges are purchased or in another sense the means by which the diagonal edges upon the peripheries of the rings are obtained. These diagonal seams are directly responsible for the already explained defect in this type of buffering wheel.

Obviously each diagonal seam 14 will produce near the periphery an acute-angled point of 15 fabric and on the other side of said seam an obtuse-angled point of fabric. The acute-angled points of fabric that engage the work in a trailing position as indicated in the upper part of Figs. 1 and 2 are marked A and the adjacent oppositely disposed obtuse angles of fabric are marked B. The acute-angled points of fabric that project towards the work as shown in the lower half of Figs. 1 and 2 are marked C and the obtuse angles of cloth supplementing them are 25 marked D.

By long use and study of buffering wheels of this type and by observation and study of the construction thereof, I have found that it is the acute-angled points of fabric such as C that project towards the work as the buffering wheel is 30 rotated in the predetermined direction that cause all the trouble, in that these acute-angled points by projecting towards the work give the article being buffed a chance to gnaw at this point until 35 the outermost stitches in its adjacent seam 14 become loosened or cut away. These acute-angled forwardly projecting points when rotated towards the work produce substantially the result that comes about when a carpenter pushes his 40 plane against the grain of a piece of wood that is somewhat cross-grained, viz: the points of the grain of wood are roughened up instead of being smoothed off.

In the lower half of Fig. 1 which represents 45 several layers in the near half of the section here illustrated, the acute-angled point of fabric C seen to the left represents the original construction with the acute angled point C still supported by the adjacent stitches of seam 14 going to the adjacent edge of the obtuse angle D. The acute-angled point C' shown in a layer still farther 50 through this section of the buffering wheel is represented as having a few of its stitches that went to the adjacent edge of the obtuse angle D' unraveled or worn out. This allows the point C' to bend or fly outwardly beyond the circle of the periphery under the action of centrifugal force 55 more or less as shown in the drawings. In the ring of fabric shown still further to the right the acute angled point C'' has had its supporting stitches of seam 14 weakened or unraveled still farther back along the seam from the periphery and allows the point C'' to project still further out beyond the periphery. It will be understood 60 that any one of these acute-angled points of fabric that would project beyond the periphery towards the work during normal rotation of the wheel (as here shown in a counterclockwise direction) would at least cause these points to scratch the work and if the work was being held in the hands of the operator might pull the work from his hands and cause damage by throwing it against the workman or around the room. When acute-angled points that would project 65 toward the work thus become loosened enough to

project beyond the periphery of the buffing wheel, the buffing wheel should be stopped and these points trimmed off.

It will be seen by reference to the upper half of Fig. 1 showing the ring of fabric 10 immediately beyond the metal ring 15 that an acute angle such as A opposite the obtuse angle B formed by the seam 14 in that ring of fabric will engage the work W in what I will call a trailing position, that is, the rotation of the buffing wheel past the work will tend to push the point back into the fabric and will not tend to unravel or break the stitches of the adjacent seam 14. It will be noted here that the obtuse angled points, either B in the further and upper half of the buffing wheel section of Fig. 1 or D in the near half of this section (shown in the lower part of Fig. 1), can not project beyond the periphery of the wheel as the fabric is continuous from the obtuse angle back to the respective securely anchored supporting areas for these points near the inner edges of these portions of the annular rings.

It may be stated that in one form of my invention I modify an already constructed buffing wheel section of the character described by eliminating these forwardly projecting, acute-angled points so that when the buffing wheel is placed into use it will not have these points of possible danger and of certain but lesser damage to the work. But in another form of my invention I provide two slightly varying processes of forming the buffing wheel sections including so shaping the buffing wheel fabric back in the process of making the sections and before the long strips of fabric are shaped into the annular rings with their edges bias-cut and with their inward portions puckered and before the said fabric is mounted within the metallic rigid rings with the opposite halves of the fabric radiating outwardly from said confining rings, so that the buffing wheel sections when originally produced or assembled, do not have these forwardly projecting acute-angled points. Such trimming back of these trouble-making points in the first form of my invention or their elimination in the second form of my invention has to be extensive enough to leave no fabric of the original point or of the eliminated point unsupported from the attachment of the fastening of the individual ring or that can possibly reach beyond the periphery.

This trimming off or original elimination of the forwardly projecting acute-angled points will be best understood by referring to the plan view of the buffing wheel of this type shown in Fig. 2. In the nearest annular ring 10' of the near half of the buffing wheel section shown and in the right hand half of the view there was originally one of these slanting or non-radial seams 14 leaving on the upper side an obtuse-angled point D and therebelow an acute-angled forwardly projecting point of fabric C. A piece of fabric 15 including this point C and all of its integral fabric extending back to a line beyond a line as 24-24 extending out radially from the axis of the buffing wheel section and shown separately in Fig. 3 has been cut away as by cutting the stitches of seam 14 from its periphery up to a point as 23 nearly to the line of the outer row of stitches 19 that secures all the annular rings 10 to the strong fabric disks 17. From there the line of severance extends on a slant as line 25 extending somewhat rearwardly relative to the direction of rotation to the periphery and forming a new and well supported obtuse angle E of fabric that cannot pro-

ject beyond the periphery of the buffing wheel and leaving a space 16 in this ring 10 the extent of which is indicated by the double pointed arrow.

Fig. 3 is a plan view of the piece 15 thus cut out from the ring 10', the said piece being shown as still having a curved peripheral line and puckered towards its inner side as it was puckered before this piece 15 was severed.

Fig. 4 is a plan view of this piece after it has been straightened or smoothed out, thus showing a straight line on the right-hand side that before was a part of the periphery of the ring 10' and showing at the top or further end of this piece 15 the straight diagonal line which with the right-hand line forms the acute-angled forwardly directed point C.

On another level and on ring 10'' shown in the left-hand portion of the lower side of Fig. 2 there is shown the space 16 from which another acute-angled forwardly projecting point C of the fabric has been removed, similar to that shown in Figs. 3 and 4. Furthermore, I may add that for a bias-cut peripheral-edged buffing wheel section of the type puckered by being mounted from within a rigid metal ring, all of the forwardly directed acute-angled points will be uniformly found in one half only of the section as divided by said metallic ring.

It is believed that a brief statement of the way in which the long strips 21 of the bias-cut edged fabric is produced and folded longitudinally incident to the puckering operation already mentioned is proper in order to explain the above statement that all of the so-called forwardly directed acute-angled points will be in one half of any given section of a buffing wheel, the division line being made by the supporting rigid ring 15 of metal and to show the step of my process just before the puckering operation where the fabric in the long strip 21 is shaped so that after the fabric is puckered and mounted on the rigid holding ring and otherwise assembled into a buffing wheel section, there will be no forwardly-projecting acute-angled points of fabric. It will be noted especially that I still have a buffing wheel section of which all parts of the periphery are bias-cut. The small pieces of fabric trimmed off as pieces 15 from the space 16 of the section shown in Fig. 2 even when its five inches of periphery is multiplied by five or six the number of dangerous points on an ordinary buffing wheel section of twelve inches diameter and having nine layers in each half will not appreciably reduce the buffing effect of the section, certainly not enough to counteract the gain of having a buffing wheel section with no dangerous or damaging points.

First, as shown in Fig. 5, a long strip or bolt of the proper buffing wheel fabric is folded lengthwise and sewed together along its edges by a special seam of stitches 26 of the nature of overcast stitching, thus forming a long tube of fabric. These stitches are of such a character that when the tube of fabric is distended, the stitches will hold the edges of the fabric in a smooth butt-to-butt joint and not in an overlapped joint. This tube of fabric is then cut or slit spirally by cuts following the dash lines 27 on the near layer of the tube as shown in the plan view thereof of Fig. 5, and by cuts following the dotted lines 28 indicating the cuts in the other or hidden half. This long spirally cut piece is then straightened out as shown in a plan view of a short portion thereof shown in Fig. 6. The seam 26 of Fig. 5 now appears as recurring angularly arranged seams 13 in a relatively wide, long

piece of fabric. This wide piece is then cut lengthwise into several pieces of the proper width according to the width desired for the annular rings 10 of the completed buffing wheel section.

Fig. 7 is a plan view of one of these relatively narrow long pieces having the recurring diagonally arranged seams 13. In Fig. 6 as well as in Fig. 7 the longitudinal edges of the long strips of fabric it will be seen are diagonally cut edges due as is well known in the art to the spiral cutting of the fabric tube of Fig. 5. The fabric of Fig. 7 is the fabric that simply from an examination of the finished buffing wheel appears to be made up of the relatively short pieces 12 of bias-cut fabric having their diagonal ends sewed together in reverse arrangement so as to produce the long strip of bias-cut material which incidentally has diagonally arranged seams uniformly slanting in one direction.

And in fact as well as in theory these long strips of Fig. 7 with their diagonally arranged seams 13 were originally made out of shorter pieces 12 of fabric cut on the bias and having such shorter pieces joined together to make the long pieces used to feed to the puckering and folding machine before the labor-saving step of forming the tube of fabric and slitting it spirally was worked out. For that reason several of the process claims omit the tube-forming step and the spirally cutting thereof and start simply with the providing of a long strip of fabric formed of shorter pieces cut on the bias with their diagonal or slanting ends sewed together by diagonally arranged seams uniformly slanting in the same direction.

Fig. 8 is a diagrammatical view of part of a long strip 21 of this bias-cut edged material being wound upon the aligned rollers of the folding and puckering machine already referred to as well known in the art and used as described to produce the buffing wheel sections of Figs. 1 and 2. Of the long strip 21 it will be seen that several layers of the fabric 21 have already been wound upon the rollers, the near one of which is shown at 30. In this view short dash lines indicate the piece of fabric 15^a that at this stage of manufacture can be cut out either by hand or by a machine operating on the near side of the strip 21 (as the parts are here shown) and on the near side of the diagonal seams 13 to eliminate according to my process what would be the forwardly-projecting acute-angled points C. By observing the position of the strip 21 that has not yet been placed on the roller 30 and its mate (unseen), it will be obvious that all of the forwardly-directed acute-angled points are at one edge (viz: the near edge as the material is shown as being handled) and plainly this condition will follow all through the different layers wound at one operation and from one piece 21 of fabric or from similar pieces 21 similarly arranged and fed to the folding and puckering machine and forming successive sections of this type of a buffing wheel.

Fig. 10 is a view similar to Fig. 8 but with the first layer of the fabric to be used for making a section of the buffing wheel as shown in Figs. 1 and 2 not yet wound upon the spaced rolls 30 and 31 and not yet puckered but with the nearer part represented as folded along its median line which in fact does happen as one of the results of the puckering operation as already described. By comparing Figs. 8 and 10 and then Figs. 1 and 2 it will be seen that the flat layer of the

fabric of Fig. 8 has in the extreme right hand portion of Fig. 10 been folded along its longitudinal median line so that the former upper faces of its two lengthwise extending halves now extend radially from the confining iron ring of Figs. 1 and 2 and what was the undersurface of the near half of the fabric of Fig. 8 now extends radially of the metal ring 15 of Figs. 1 and 2 and faces the observer as appears in Figs. 1 and 2 and contains all the forwardly-directed acute-angled points. In a similar manner and from a similar swinging of the material through an angle of 90 degrees, the upper surface of the further longitudinal half of the fabric of Fig. 8 has become the surface that faces the observer in the rings 10 of the further half of the buffing wheel section of Figs. 1 and 2 appearing in the upper half of each of those views and has all the rearwardly directed acute-angled points A.

20 What I claim as new is:

1. In a buffing wheel of the one-way rotation type, and having a rigid center and projecting therefrom a working zone reaching to the periphery and composed of annular rings of fabric 25 having their periphery cut on the bias, said rings being formed of long strips of fabric puckered on their edges toward said solid center, said long strips being formed of shorter pieces of fabric cut on the bias with their angular ends sewed 30 to adjacent short pieces resulting in seams extending diagonally of said long strips producing an acute angle of fabric on one side of each seam adjacent the periphery and an obtuse angle on the other side, the acute angles that would 35 project towards the work being trimmed off to make an obtuse angle.

2. In a buffing wheel of the one-way rotation type, and having a rigid center and projecting therefrom a working zone reaching to the periphery and composed of annular rings of fabric 40 having their periphery cut on the bias, said rings being formed of long strips of fabric puckered on their edges toward said solid center, said long strips being formed of shorter pieces of fabric 45 cut on the bias with their angular ends sewed to adjacent short pieces resulting in seams extending diagonally of said long strips producing an acute angle of fabric on one side of each seam adjacent the periphery, and an obtuse angle 50 on the other side, the acute angles that would project towards the work being trimmed off to make an obtuse angle, so that the remaining acute angles engage the work in a trailing position which with all the obtuse angles whether 55 engaging the work in a projecting or trailing position, have no tendency from centrifugal action to project beyond the periphery of the wheel.

3. In a buffing wheel of the one-way rotation type, and having a rigid center and projecting 60 therefrom and secured thereto a working zone reaching to the periphery and composed of annular rings of fabric having their periphery cut on the bias, said rings being formed of long strips of fabric folded lengthwise through their center 65 and puckered on their edges toward said solid center, said long strips being formed of shorter pieces of fabric cut on the bias with their angular ends sewed to adjacent short pieces resulting in seams extending diagonally of said long strips, 70 producing an acute angle of fabric on one side of each seam adjacent the periphery and an obtuse angle on the other side, the acute angles that would project towards the work being trimmed off to make an obtuse angle.

4. In a buffing wheel section having a rigid

center and therebeyond a working zone formed of a plurality of rings of flexible fabric secured at their inner portions to said rigid center and adapted to be held distended by centrifugal action, said rings being formed of long strips of fabric puckered near their edges towards said solid center, said long strips being formed of shorter pieces of woven fabric cut on the bias with their angular ends sewed to the reversely arranged angular ends of adjacent short pieces, resulting in seams extending diagonally of said long strips and producing an acute angle of fabric on one side of each seam adjacent the periphery of the wheel and an obtuse angle on the other side of the seam, the acute angles that would project towards the work when the wheel is rotated in the predetermined direction being trimmed off to make an obtuse angle so that there are no forwardly projecting acute angles to project beyond the circle of the periphery when a seam becomes loosened near the periphery.

5. In a buffering wheel section having a rigid center and therebeyond and secured thereto a working zone formed of a plurality of rings of flexible fabric secured at their inner portions to said rigid center and adapted to be held distended by centrifugal force, said rings being formed of long strips of fabric folded lengthwise through their center and puckered near their edges towards said solid center, said long strips being formed of shorter pieces of woven fabric cut on the bias with their angular ends sewed to the reversely arranged angular ends of adjacent short pieces, resulting in seams extending diagonally of said long strips and producing an acute angle of fabric on one side of each seam adjacent the periphery of the wheel and an obtuse angle on the other side of the seam, the acute angles that would project towards the work when the wheel is rotated in the predetermined direction being trimmed off to make an obtuse angle so that there are no forwardly projecting acute angles to project beyond the circle of the periphery when a seam becomes loosened near the periphery.

6. In a buffering wheel section having a rigid center and therebeyond and secured thereto a working zone formed of a plurality of rings of flexible fabric secured at their inner portions to said rigid center and adapted to be held distended by centrifugal force, said rings being formed of long strips of fabric arranged at their longitudinal center about the inside of a rigid ring with the opposite halves of the strips extending to the periphery and puckered adjacent said rigid ring, said long strips being formed of shorter pieces of woven fabric cut on the bias with their angular ends sewed to the reversely arranged angular ends of adjacent short pieces, resulting in seams extending diagonally of said long strips and producing an acute angle of fabric on one side of each seam adjacent the periphery of the wheel and an obtuse angle on the other side of the seam, the acute angles that would project towards the work when the wheel is rotated in the predetermined direction being trimmed off to make an obtuse angle so that there are no forwardly projecting acute angles to project beyond the circle of the periphery when a seam becomes loosened near the periphery.

7. A buffering wheel section having a rigid center and secured thereto and projecting therefrom a working zone composed of annular rings of flexible woven fabric having their periphery bias-cut, said rings being formed of long strips of woven

fabric folded lengthwise through their center and puckered on their edge toward said solid center and having diagonally extending seams normally producing an acute angle of fabric on one side of each seam adjacent the periphery and an obtuse angle of fabric on the other side of the seam, the said acute angles of fabric that would project towards the work when the wheel is rotated in the predetermined direction being trimmed off to make an obtuse angle, so that the remaining acute angles engage the work in a trailing position.

8. A buffering wheel composed of a central solid core and secured thereto and projecting radially therefrom a plurality of annular rings of flexible, woven fabric, said rings being formed from a roll of bias-cut fabric arranged within a rigid metal ring with its halves spread radially outward from said metal ring, each of said halves forming one of said annular rings and having only a bias-cut edge at their peripheries, said rings having diagonally arranged seams extending inwardly from the periphery of the wheel and normally producing an acute angle of fabric on one side of each seam adjacent the periphery and an obtuse angle of fabric on the other side of the seam, the said acute angles of fabric that would normally project towards the work when the wheel is rotated in the predetermined direction being trimmed off to an obtuse angle substantially back to the point of support.

9. The process of making buffering wheel sections of the type having a rigid central core and projecting therefrom a working zone composed of a plurality of annular rings of flexible woven fabric with their peripheral edges bias-cut which process consists of providing such rigid cores, converting a length of woven fabric into a tube by sewing together the opposite longitudinal edges of said length of fabric, cutting said tube spirally forming a relatively wide length of fabric with its threads on the bias and its longitudinal edges bias-cut and with portions of said original seams diagonally arranged at recurring intervals, cutting said relatively wide length of fabric lengthwise into long strips twice the width of the required annular rings and each having said recurring diagonal seams and each producing at each periphery an acute and an obtuse angle of fabric adjacent the edge of the strip and having its longitudinal edges bias-cut, then winding enough of such a strip about and spaced out from one of said central rigid cores to make a roll having layers equal in number to half the desired annular rings of a section meanwhile cutting off the acute angles of fabric on the side of said roll where the said angles would point to the work when the section is rotated in the predetermined direction, compressing the center of said roll toward said core, then placing a rigid metal ring around the center of said roll on the core and turning the fabric on the opposite sides of the ring outward radially and securing the fabric of a section to its core.

10. The process of making buffering wheel sections of the type having a rigid central core and a working zone projecting therefrom composed of a plurality of annular rings of flexible woven fabric with their peripheral edges bias-cut, which consists of providing such rigid cores, providing a long length of woven fabric composed of shorter pieces of fabric cut on the bias and connected lengthwise by similarly arranged diagonally ex-

tending seams so that the longitudinal edges are bias-cut and there are acute angled points of fabric on one side of each said seam at each edge of the strip and obtuse angled points at the other side of the seam; placing in spaced relation about one of said cores layers of said strip, half in number of the rings desired in a section and meanwhile cutting off the acute angles of fabric on the side of the roll where the angles would point to the work when the section is rotated in the predetermined direction, compressing the center of said roll to the core to form a puckering of the rings on their edge nearest the core, placing a rigid metal ring around said puckered center of the roll and then turning the fabric on the opposite sides of the metal ring outward radially and securing the fabric of a section to its core.

11. The process of making buffing wheel sections of the type having a rigid central core and projecting therefrom a working zone composed of a plurality of annular rings of flexible woven fabric with their peripheral edges bias-cut, which process consists of providing such rigid cores, converting a length of woven fabric into a tube by sewing together the opposite longitudinal edges of said length of fabric, cutting said tube spirally forming a relatively wide length of fabric with its threads on the bias and its longitudinal edges bias-cut and with portions of said original seams diagonally arranged at recurring intervals, cutting said relatively wide length of fabric lengthwise into long strips twice the width of the required annular rings and each having said recurring diagonal seams and each producing at each periphery an acute and an obtuse angle of fabric adjacent the edge of the strip and having its longitudinal edges bias-cut, cutting off the acute angles of fabric on the side of strip where the angles would point toward the work when the 40

section is rotated in the predetermined direction and winding enough of said strip about and spaced out from one of said central rigid cores to make a roll having layers equal in number to half the desired annular rings of a section, compressing the center of said roll toward said core, then placing a rigid metal ring around the center of said roll on the core and turning the fabric on the opposite sides of the ring outward radially and securing the fabric of a section to its core.

12. The process of making buffing wheel sections of the type having a rigid central core and a working zone projecting therefrom composed of a plurality of annular rings of flexible woven fabric with their peripheral edges bias-cut, which consists of providing such rigid cores, providing a long length of woven fabric composed of shorter pieces of fabric cut on the bias and connected lengthwise by similarly arranged diagonally extending seams so that the longitudinal edges are bias-cut and there are acute angled points of fabric on one side of each said seam at each edge of the strip and obtuse angled points at the other side of the seam cutting off the acute angles of fabric on the side of strip where the angles would point toward the work when the section is rotated in the predetermined direction and winding enough of said strip about and spaced out from one of said central rigid cores to make a roll having layers equal in number to half the desired annular rings of a section, compressing the center of said roll to the core to form a puckering of the rings on their edge nearest the core, placing a rigid metal ring around said puckered center of the roll and then turning the fabric on the opposite sides of the metal ring outward radially and securing the fabric of a section to its core.

HENRY R. BENBOW.
